UNITED STATES PATENT OFFICE.

WILLIAM BIEBER, OF NEW YORK, N. Y.

MEANS FOR MAKING FIREPROOF WALLS.

No. 834,253.

Specification of Letters Patent.

Patented Oct. 30, 1906.

Application filed July 13, 1906. Serial No. 326,150.

To all whom it may concern:

Be it known that I, WILLIAM BIEBER, a citizen of the German Empire, residing at New York, in the county of New York and 5 State of New York, have invented certain new and useful Improvements in Means for Making Fireproof Walls, of which the following is a specification.

The invention to be hereinafter described 10 relates to means for making fireproof walls in or forming part of a building, and more particularly to such walls as are formed of a quick-setting composition. In the formation of such walls it is desirable that the apparatus employed may have a wide range of 15 application not only in the formation of walls during the construction of a building, but also in construction of such walls in buildings already erected. Such walls require to be of 20 different thicknesses and of varying heights, the walls being also preferably formed as a substantially one-piece or continuous structure.

With these general considerations in view 25 the object of the present invention is to provide a device of the character referred to which shall be simple in construction, easy of manipulation, readily put up or taken down, and wherein the parts may be adjusted for 30 the formation of fireproof walls of widely-different forms and sizes.

The invention consists of the parts and combinations to be hereinafter fully described and then definitely pointed out in 35 the claims.

In the drawings which illustrate one of the practical embodiments of the present invention, Figure 1 is a general side view of the device in use. Fig. 2 is a sectional view on the 40 line $x-x$, Fig. 1. Fig. 3 is an enlarged detached view of one end of a wall-formation board, showing the bearing strip and rollers. Fig. 4 is a detail sectional view of a slightly-modified form of side post, showing the engagement of the bearing-strip therewith; and 45 Fig. 5 is a like view showing the bearing-roller engagement with the post-track.

In the formation of fireproof walls, either in the erection of buildings or in providing partitions in buildings already erected, one of the important considerations is to employ a composition which will set quickly and when set 50 will be self-sustained, free from cracks, and

substantially continuous, and I employ in the present instance such compositions in which 55 cement or asbestos, sand, caustic potash, and water constitute the principal constituents.

In the drawings, A represents the exterior walls of a building, A' the floor, and A² the ceiling or roof, all of which may be of any 60 usual or desired construction. The drawings illustrate the formation of a comparatively short section of interior fireproof wall; but it is to be understood that it may be more extensive and may be the exterior wall itself. 65

Disposed between the floor A' and ceiling or roof A² are the series of posts B B, which are preferably formed of T metal, as shown, although other suitable material may obviously be employed, the said posts being disposed in pairs, as shown by Fig. 2, the posts of each pair being a distance apart equal to the thickness of the wall to be formed. These posts are secured in place by means of wedges b' b', reversely inclined, as shown in Fig. 1, 70 and when driven in place between the ceiling or roof A² and the top of the post they may be locked by means of a pin b², which engages locking-notches in the adjacent surfaces of the wedges. It will be noted that the locking-notches in the wedges b b' are disposed at 75 different relative positions along the wedge incline, so that as the wedges are driven more or less to place at least a pair of notches will coincide at some point along the wedge 80 incline and enable the locking-pin to engage them.

The wall-formation boards C are of proper dimensions to extend between adjacent posts, as shown, and at each end they are provided with bearing-strips c, which overlap the side flanges of the posts B and position the formation-boards C, so that the inner surfaces thereof extend in the same plane with the inner surfaces of posts B, with the result 90 that upon removal of the posts and boards the material forming the wall will present a uniform and continuous surface. The bearing-strips c may be secured in their overlapping position to the formation-boards C by 95 any suitable means—as, for instance, the bolts c'.

In order to secure the formation-boards C in fixed position, each is provided with locking-bolts d d at each end, which engage appropriate holes or perforations in the out- 100

wardly-extended flange of the T-posts B, as best indicated in Fig. 2 and as will be readily understood by one skilled in the art.

From the construction thus far described 5 it will be noted that the posts B B being fixed in position the formation-boards C C are secured in pairs, one opposite the other, to the posts by means of the sliding bolts d d, the bearing-strips c at such times correctly positioning the inner surfaces of the formation-boards in the plane of the inner surface of the posts. The composition is now placed 10 between the opposed boards, and when it sets the boards are loosened by withdrawing the bolts d d and raised so that their lower edges just overlap the set composition below, whereupon the operation is repeated. During the raising of the formation-boards the bearing-strips travel along the flange of the 15 posts, as upon a track. The bearing-boards, however, are necessarily made sufficiently heavy to withstand the use to which they are put, and braces f f may extend lengthwise thereof near the top and bottom.

20 Between the top and bottom edges of the formation-boards the bearing-strips c are preferably provided with a circularly-shaped recess h' h', Fig. 3, and seated therein are the guide-wheels h h, the peripheries whereof extend beyond the outer edge of the bearing-strips c and contact with the side of the central flange of the T-posts B, which acts as a track for the upward movement of the formation-boards.

25 In Figs. 4 and 5 a slightly-modified form of the posts are shown wherein the posts B' are provided also with a bead b¹⁰ on each side of the central web, and between this bead and the lower flange is thus formed a guide or 30 track way for the bearing-strip and guide-wheels, as indicated, which will thus resist any outward movement of the formation-boards.

35 From the construction described it will be seen that the posts are readily, securely, and yet detachably put in place; that there may be any number of these desired, according to the extent of the wall to be made; that the formation-boards may be readily put in 40 place, beginning at the lower part of the wall to be made, and after the composition M has become set between opposed formation-boards that these may be readily raised to make another superposed mass, and so on to 45 the top. When the top is reached, only one formation-board of a pair is put in place, to thereby leave a space for the introduction of the composition, a suitable plate being employed to smooth over the exposed side of 50 this last layer of composition. When the wall thus constructed has properly set, which it will do in a few minutes, the formation-board and posts are removed, the wedges lending themselves readily to displacement

for this purpose. It is obvious, of course, 65 that the posts might be put permanently in place, if desired.

Having thus described my invention, what I claim, and desire to secure by Letters Patent, is—

70 1. In an apparatus for forming fireproof walls, the combination of a series of posts or uprights, means for securing them in place in pairs, one opposite the other, a series of wall-formation boards, means for securing them in pairs to said posts or uprights, one opposite the other, said formation-boards being provided with bearing-strips to position the inner surface of said formation-boards in the plane of the inner surfaces of 75 the posts or uprights.

75 2. In an apparatus of the class described, the combination of a series of posts, means for temporarily securing said posts in position in pairs, one opposite the other at the 80 desired distance apart, a series of wall-formation boards, each having an overlapping bearing-strip to bear upon an outer surface of a post to position the inner surface of the board in the plane of the inner surface of the 85 post, fastening devices carried by the formation-boards, and provisions on the posts for coacting with said devices to hold the boards in desired position while putting composition in place.

90 3. In an apparatus of the class described, the combination of a series of posts, wedges for securing the posts temporarily in position in pairs, one opposite the other at the desired distance apart, a series of wall-formation boards, each having an overlapping bearing-strip to bear upon an outer surface of a post to position the inner surface of the formation-boards in the plane of the inner 95 surface of the posts, fastening devices carried by the formation-boards, and provisions on the posts for coacting with the said fastening devices to hold the boards in position while putting composition in place.

100 4. In an apparatus for forming fireproof 100 walls, the combination of a series of posts or uprights, means for securing them in place in pairs, one opposite the other, a series of wall-formation boards, means for securing them in 105 pairs to said posts or uprights, one opposite the other, said formation-boards being provided with bearing-strips to position the inner surface of said formation-boards in the plane of the inner surfaces of the posts or uprights, and guide-wheels carried by the 110 formation-boards and bearing on the posts.

115 5. In an apparatus for making fireproof 115 walls, the combination of a series of T-posts, means for securing them in pairs, one opposite the other, the central flange of the posts being provided with holes or perforations, a series of wall-formation boards, each having 120 a bearing-strip to bear upon the flange of a

post to thereby bring the inner surface of the post and board in the same plane, and bolts carried by the formation-boards for engaging the holes in the central flange of the posts 5 to lock the parts in position.

6. In an apparatus for making fireproof walls, the combination of a series of T-posts, means for securing them in pairs, one opposite the other, the central flange of the posts 10 being provided with holes or perforations, a series of wall-formation boards, each having a bearing-strip to bear upon a flange of a post to thereby bring the inner surface of

the post and board in the same plane, bolts carried by the formation-boards for engaging 15 the holes in the central flange of the posts to lock the parts in position, and guide-wheels carried by the formation-boards and engaging the posts.

In testimony whereof I affix my signature 20 in presence of two witnesses.

WILLIAM BIEBER.
